(57) **CLAIM**

The ornamental design for a portable illuminator, as shown and described.

DESCRIPTION

FIG. 1 is a perspective view of a portable illuminator showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a reference showing the portable illuminator when it is in use.

The broken line showing of the pages are for illustrative purposes only and forms no part of the claimed design.
